UNITED STATES PATENT OFFICE.

RUBEN QUIST, OF LOHRVILLE, IOWA.

PROJECTILE.

1,230,217.

Specification of Letters Patent. Patented June 19, 1917.

Application filed November 6, 1915. Serial No. 59,981.

To all whom it may concern:

Be it known that I, RUBEN QUIST, a citizen of Sweden, residing at Lohrville, in the county of Calhoun and State of Iowa, have 5 invented certain new and useful Improvements in Projectiles, of which the following is a specification.

This invention relates to improvements in projectiles and more particularly to a projectile designed primarily for the destruction of dirigibles, air-ships and air craft generally in time of war. Its object then is to produce a bomb which may be timed so that when its speed through the air is known 10 it can be timed to explode at a given distance from its mortar. Novel means for setting or timing the bomb and for exploding the same through the operation of internal mechanism constitute further objects. 15 With the foregoing and other objects in view the invention consists in the combination and arrangement of parts to be herein-after fully described in the following specification, pointed out in the appended claims 20 and illustrated in the accompanying drawings which form a part of said specification and in which—

Figure 1 is a view partly in vertical section and partly in side elevation of my improved bomb.

Fig. 2 is a view of the bomb in elevation ready to be consigned to its mortar to be discharged.

Fig. 3 is a vertical sectional view of the 35 bomb with part of the interior mechanism removed.

Fig. 4 is a cross section on line 4—4 of Fig. 3.

Fig. 5 is a cross sectional view on line 5—5 40 of Fig. 3.

Fig. 6 is a cross section on line 6—6 of Fig. 9.

Fig. 7 is a plan view of the mechanism that controls the explosion of the bomb.

Fig. 8 is an end view of Fig. 7.

Fig. 9 is a front view of the same.

Fig. 10 is a view of the automatically controlled weight and its connections.

Fig. 11 is a similar view of the same with 50 the weight in an altered position.

Fig. 12 is a plan view of the bomb, with the cap removed and part of the interior mechanism eliminated, showing the application of the timing lever.

Fig. 13 is a view of Fig. 12 in elevation. 55 Like reference characters indicate cor-

responding parts throughout the several views.

The reference numeral 1 denotes the shell provided with a removable screw cap 2 and 60 formed with an annular collar 3 which serves as a rest or stop for the outer edge of a cover 4 adapted to fit snugly upon the top of a powder reservoir 5 disposed within the shell 1 and spaced away from the inner periphery thereof to afford store space for shrapnel 6, the upper end of this shrapnel container being also closed by the cover 4. The cover 4 is formed with a perforation in alignment with a similar perforation in the 65 base of a frame 7 secured to said cap and a detonator 8 is arranged in said perforated portions in the plane of movement of a hammer 9 carried by an angular lever 10 pivoted to the frame 7 and formed with a depending 70 ear 11 to which a spring 12 is secured that is carried by a lug 13 secured to the frame base.

The lever 10 in raised position, Fig. 1, is capable of releasable engagement with a crank 13^a carried by the frame. A discharge wheel 15 having peripheral teeth 14 is slidably keyed to a plunger shaft 16, formed with transverse perforations 17, 18, that carries a loose weight 19 and a fixed yoke 20 having flexible terminations capable 85 of frictional engagement with said weight. The shaft 16 at its lower end rests in the recessed portion 21 of a lever 22 which is pivoted in bearings 23 secured to the frame base and which operates between a pair of 90 upright guides 24 also secured to said frame base, the end of the lever 22 being spaced away from the floor base by a coil spring 25. The lever 22, further, carries a dog 26 adapted for engagement with the teeth 27 95 of a large gear wheel 28 fast upon a shaft 29 journaled in bearings 30 carried by the frame, the teeth of said wheel being also in mesh with the teeth 14 of the discharge wheel 15 and with the pinion 31 fast upon 100 a shaft 32 journaled in bearings 33 carried by the frame, said shaft carrying a spring 34 one end of which is secured to a bracket 35 carried by the frame base. The end of the shaft 32 is of a shape to receive the key 105 36 whereby it may be rotated, under certain conditions, to permit the spring 34 to be wound thereupon.

The discharge wheel 15 carries an angular finger 37 that projects beyond its periphery 110 and is capable of engagement, as said wheel rotates, with the crank 13 to swing the same

- out of engagement with the lever 10 to permit the spring 12 thereof to move the same toward the frame base and the hammer 9 into engagement with the detonator 8 to explode the powder in the reservoir 5. The outer periphery of the shell 1 is marked, as shown in Fig. 2, to denote the number of yards it is intended the projectile shall travel from its mortar previous to the explosion.
- 10 First the speed at which the projectile will travel is determined by suitable experiments, and the length of time required for a complete turn of the wheel 15 is also determined. It will be noted the shaft 32 is rotated by the spring 34 and said shaft rotates the pinion 31 which turns the wheel 28 which turns the said wheel 15. To set or time the bomb a handle 38 is placed in engagement with the finger 37 and shaft 16 to rotate the same; 15 said handle is provided with an indicator 39 which travels about the periphery of the shell with said handle, when the cap is removed, and which may be stopped opposite any of the marks 40 of said shell desired, to 20 correspond to the point at which the explosion is desired, with relation to the mortar. With the yoke embracing the weight 19 the bomb as set and shown in Fig. 1 is ready. The spring 25 yieldingly retains the weight 25 19 and shaft 16 and lever 22 in raised position. The cap 2 is now placed upon the shell and the latter placed in the mortar and fired. The impact which causes the ejection of the projectile from the mortar will force the 30 weight out of the yoke, into the position shown in Fig. 11, and depress the lever 22 thus freeing wheel 28 of dog 26 and starting the mechanism. It is not possible for the spring 25 to return the weight 19 and lever 35 22 to normal position after the projectile is discharged from the mortar as the ends of the yoke will contract materially when relieved of the weight. When the wheel 15 which has been set in motion by the spring 40 34 and connection causes the finger 37 to contact with the crank 13^a the charge will be exploded as previously described.
- 45 What is claimed is:—
1. In a projectile comprising a powder reservoir, a frame carried thereby, a spring-pressed hammer carried by said frame to explode the powder, means carried by said frame normally engaging said hammer to retain the same in inoperative position, a 50 spring shaft journaled in said frame, a toothed wheel fast upon said shaft, a plunger shaft journaled in said frame, means associated with said plunger shaft and frame whereby the former is yieldingly retained in 55 adjusted relation, said means also engaging said toothed wheel to retain the same in set position, a second toothed wheel slidably
  - 60 keyed upon said plunger shaft and in mesh with the first named toothed wheel, a finger carried by said second toothed wheel for engagement with the said hammer-engaging means, and a handle adapted for releasable engagement with said plunger shaft to rotate the same to set the mechanism.
  - 65 2. In a projectile comprising a powder reservoir, a frame carried thereby, a spring-pressed hammer carried by said frame to explode the powder, means carried by said frame normally engaging said hammer to retain the same in inoperative position, a 70 spring shaft journaled in said frame, a toothed wheel fast upon said shaft, a plunger shaft journaled in said frame, means associated with said plunger shaft and frame whereby the former is yieldingly retained in 75 adjusted relation, said means comprising a weight and yoke, fast and loose respectively, on said shaft, said yoke normally engaging said weight, connection between said last named means and said toothed wheel for 80 normally retaining the latter in set position, a second toothed wheel slidably keyed on said plunger shaft in mesh with said first named toothed wheel, a finger carried by said first named toothed wheel for engagement with said hammer-engaging means, and a handle adapted for engagement with 85 said plunger shaft to rotate and set the same.
  - 90 3. In a projectile comprising a powder reservoir, a frame carried thereby, a spring-pressed hammer carried by said frame to explode the powder, means carried by said frame normally engaging said hammer to retain the same in inoperative position, a spring shaft journaled in said frame, a toothed wheel fast upon said shaft, a plunger shaft journaled in said frame, a weight and yoke, fast and loose respectively, upon said shaft and normally in embraced relation, a recessed lever engaging said plunger 95 shaft to yieldingly retain the same in normal or raised position, a dog carried by said recessed lever to normally engage said toothed wheel to lock the same against rotation, a second toothed wheel slidably 100 keyed upon said plunger shaft in mesh with said first named toothed wheel, a finger carried by said wheel for engagement with the said hammer-engaging means, and a handle adapted to engage said plunger shaft to 105 rotate and set the same.
- 110 In testimony that I claim the foregoing as my own I have hereto affixed my signature in the presence of two subscribing witnesses.
